LEWIS W. WILLIAMS, OF MORRIS TOWNSHIP, MORRIS COUNTY, NEW JERSEY, ASSIGNOR TO MOTOR IMPROVEMENTS, INC., OF NEWARK, NEW JERSEY, A CORPORATION OF DELAWARE

FLAME ARRESTOR FOR CARBURETORS

Application filed April 9, 1930. Serial No. 442,770.

This invention relates to a flame arrester for the carburetor of an internal combustion engine for preventing explosions or fires from the back-firing of the engine and has as an object a simple, efficient and economical flame arrester for preventing such occurrences.

A device embodying this invention comprises a metallic filter arranged at the mouth of the carburetor or intake. This filter is provided with a narrow inlet of sufficient total area to permit flow to the intake of the required amount of air for proper operation of the engine. However, the inlet is sufficiently narrow that in the event of back-firing of the engine, the flame is retained within the filter and is thus prevented from being communicated to the surrounding atmosphere. Thus, although the engine may be surrounded by combustible fumes, the possibility of an explosion or conflagration is effectively prevented.

Other objects, novel features and advantages of this invention will be apparent from the following specification and accompanying drawing, wherein:

Fig. 1 is a side elevation of an internal combustion engine, the carburetor of which is provided with a flame arrester embodying the invention.

Fig. 2 is a side elevation of the flame arrester.

Fig. 3 is an enlarged fragmentary section on the line 3—3 of Fig. 2, and

Fig. 4 is a perspective view of a portion of the device.

In Fig. 1, 10 represents a conventional internal combustion engine provided with a carburetor 11 having an air intake pipe 12, at the mouth of which is arranged the flame arrester 13. The flame arrester comprises a hollow substantially cylindrical casing 14. The upper end of the casing terminates in an inwardly projecting neck 15 and the lower end of the casing terminates in an outwardly projecting collar 16. The collar 16 fits over the end of the intake pipe 12 and a bracket 17 has one end snugly fitting within the neck 15 and the other other end attached to the en-

gine. The flame arrester is thus supported by the intake pipe and the bracket.

The casing 14 is provided with a pair of peripheral ridges 18 and 19 and between these ridges the casing 14 is longitudinally fluted as at 20. In the grooves formed by the fluting there are provided rows of apertures 21. A helix surrounds the casing 14 with its bottom turn in contact with the ridge 18 and its top turn in contact with the ridge 19. This helix is formed from a ribbon 22 which is preferably preformed so that it naturally assumes helical shape. At regular intervals projections 23 extend from one face of the ribbon and provide means for spacing apart the adjacent turns. These projections are very minute so that the space between adjacent turns is very narrow. The projections 23 form a large number of narrow slots which constitute the air intake. The ribbon 22 is several times as wide as it is thick, but due to the preforming of the ribbon with suitable curvature, the turns lie evenly and are uniformly spaced.

The total inlet area formed by the spacing of the turns of the helix is sufficient to allow the flow of the required amount of air for proper operation of the engine with which the device is used. However, the width of the inlet slot is so restricted as to prevent the passage of flames therethrough. The width of the slot may be of the order of 1/1000ths of an inch, but may be varied as conditions justify. Also, the width and thickness of the ribbon may be varied to meet different conditions.

The normal operation of an engine is not affected by the use of the flame arrester above described. Air passes through the inlet slot provided in the helix and through apertures 21 into the interior of the container from whence it flows through the intake 12 into the carburetor 11 where it is mixed with gasoline in the well-known manner to form a fuel mixture for the engine. The device also serves to filter out from the air solid particles which otherwise would be taken into the carburetor. In the event of the engine back-firing, the flame is confined within the casing 14

and is effectively prevented from being communicated to any combustible fumes that might be in the vicinity of the engine and the possibility of explosion from conflagration 5 due to the back-firing of the engine is thus effectively eliminated.

It is of course understood that various modifications may be made in the device above described without in any way departing from 10 the spirit of the invention as defined in the appended claims.

I claim:

1. In combination with the carburetor of an internal combustion engine, a tubular 15 member composed of a helically wound ribbon having projections spacing apart successive turns, the passages thus provided being sufficiently restricted to prevent the passage of flame therethrough, a fluted hollow 20 member enclosed by and supporting said member and forming channels therewith, said supporting member having apertures establishing communication between said channels and the interior of the supporting 25 member, and a conduit leading from the interior of the supporting member to the carburetor.

2. In combination with the carburetor of an internal combustion engine, a tubular 30 member composed of a ribbon wound helically with its wide faces normal to the axis, means spacing the turns of said helix to provide narrow slots which will pass air and prevent passage of flame, a fluted hollow member 35 surrounded by said tubular member and forming channels therewith, said hollow

member having apertures providing communication between said channels and the interior of the supporting member, and a conduit leading from the interior of the supporting member to the carburetor.

3. A flame arrester for use with the carburetor of an internal combustion engine comprising a tubular member composed of a metal ribbon wound helically with its wide faces normal to the axis of the helix and having projections spacing apart the successive turns to provide passages sufficiently restricted to prevent passage of flame therethrough, and end members for said tubular member, 70 one of said end members being adapted for attachment to the air intake pipe of the carburetor.

4. A flame arrester for use with the carburetor of an internal combustion engine comprising a tubular member composed of a metal ribbon wound helically with its wide faces normal to the axis of the helix and having projections spacing apart the successive turns, the passages thus provided being sufficiently restricted to prevent the passage of flame therethrough, a hollow member enclosed by and supporting the helix, and apertures in said supporting member establishing communication between said passages and the interior of the supporting member, said supporting member having provision for attachment to the air intake pipe of the carburetor.

In testimony whereof, I have signed my name to this specification.

LEWIS W. WILLIAMS.
